US00D956469S

(12) United States Design Patent (10) Patent No.: US D956,469 S
(45) Date of Patent: * Jul. 5, 2022

(54) ELECTRIC INDUCTION COOKER

(71) Applicant: BEIJING XIAOMI MOBILE SOFTWARE CO., LTD., Beijing (CN)

(72) Inventors: Jing Jiang, Beijing (CN); Ningning Li, Beijing (CN); Baowen Zhao, Beijing (CN)

(73) Assignee: BEIJING XIAOMI MOBILE SOFTWARE CO., LTD., Beijing (CN)

() Term: 15 Years

(21) Appl. No.: 35/511,714

(22) Filed: Oct. 13, 2020

(80) Hague Agreement Data

Int. Filing Date: Oct. 13, 2020

Int. Reg. No.: DM/211506

Int. Reg. Date: Oct. 13, 2020

Int. Reg. Pub. Date: Apr. 16, 2021

(30) Foreign Application Priority Data

Apr. 14, 2020 (CN) 202030147354.5

(51) LOC (13) Cl. 07-02

(52) U.S. Cl.
